PROCESS OF TREATING IMPURE CRUDE OIL

Filed Jan. 26, 1924

John F. Wright Inventor

By Jesse R. Stone his Attorney

his Attorney

UNITED STATES PATENT OFFICE.

JOHN F. WRIGHT, OF EL DORADO, ARKANSAS.

PROCESS OF TREATING IMPURE CRUDE OIL.

Application filed January 26, 1924. Serial No. 688,633.

My invention relates to a process of treating petroleum oil to free it of impurities and break up emulsions of such oil with water, basic sediment and other objectionable matter.

It is an object of my invention to provide a method of treating impure crude oil whereby it may be cleaned of impurities without the use of chemicals.

Another object is to clean the oil of its impurities largely through agitation and settling under heat without the loss of the lighter distillates through evaporation in a simple and economical manner.

It is now common to cause the separation of oil and its emulsions of oil and basic sediment by methods including the use of heat and chemicals through the use of costly apparatus or by electrical dehydration, centrifugal machines and similar processes involving a costly installation and expensive upkeep. The process devised by me is intended to be simple economical and continuous.

Referring to the drawing herewith wherein a preferred embodiment of my invention is disclosed, Fig. 1 is a central longitudinal section through an installation employing my invention; Fig. 2 is a transverse section through my propeller wheel. Like numerals of reference are employed to designate like parts in all the views.

In carrying out my invention I employ a large treating tank 1 having in the bottom 25 of the same a series of steam coils 2 tending to heat the contents of the tank. At one side of the bottom is a chamber 3 boxed off from the rest of the tank but having a perforated top 4. This forms a super-heater 40 from which water is drawn to mix with the oil to be treated through an outlet pipe 5. The steam pipes passing through this chamber maintain the water therein at high temperature.

The oil to be treated, I desire to thoroughly mix in atomized form with a spray of hot water. I do this by spraying the oil with hot water drawn from the pipe 5 into a closed chamber 6, mounted at 7 on the arched upper end 8 of the tank. The two liquids are pumped in under pressure 50 through two inclined nozzles 9 and 10, the nozzle 10 being connected with a source of supply of oil under pressure and the pipe 5 taking hot water from the coil 2 under the action of the pump shown in the drawing.

Within the chamber is a propeller wheel 11 mounted on a vertical stub shaft 12 having bearings in the frame work of the housing. The blades or vanes 13 of the propeller 60 are radial but have their outer ends curved rearwardly so as to better receive the impulse of the jets of liquid from the spray nozzles, thus causing the rotation of the propeller. 65

On the shaft 12 below the propeller is a crown gear wheel 14, positioned to mesh with a smaller gear 15, upon a shaft 16 extending downwardly into the treating tank and having a bearing at 17, in a spider 18 70 at the lower end of a cylindrical tube or agitating pipe 20. This tube is secured to the upper end 8 of the tank and extends to a point immediately above the steam coils 2. The lower end is open and the fluid discharged downwardly will strike a horizontal baffle 21 below the outlet and secured to the tube by connecting strips 22. 75

Mounted upon the shaft 16 are a series of agitating members comprising longitudinal 80 paddles or blades 23 at the upper end. Below these blades are radial agitating vanes 24 curved to impart a downward drive upon the liquid. Below these blades is a spiral or screw blade 19, also adapted to impart 85 a downward motion to the liquid during rotation of the shaft.

Within the tank and fitting about the tube 20 are a plurality of horizontal perforated baffles 25 to assist in the separating of the 90 water from the oil and acting to divide said tank into a plurality of vertically arranged settling chambers.

In the operation of the device, oil and hot water are sprayed under pressure against 95 the blades of the propeller 11. The nozzles are inclined so that the sprays will be intimately mixed and the oil acted upon by the hot water. The mixture of oil and water will be drawn down into the tube to where 100 it will be further agitated and broken up by the blades and driven forcibly downward by the blades 24 and 19. The agitation of the liquids by the apparatus in the casing 6 and tube 20 assist in breaking up 105 the particles of impurities in the oil whereby they are enabled to settle out thereafter.

The mixture issues from the tube 20 against the plate 21 and is deflected up away 110 from the steam pipes and through the perforations in the baffles 25. This serves to retard the flow and breaks up the bubbles

which may form and allows the water and sediment to settle out.

This oil which rises to the top will be free of emulsion and may be drawn off through an outlet pipe 26 to a storage tank 27. It will be noted that this process can be made continuous, it being only necessary to clear the treating tank of settling at intervals through outlet 28. The employment of the suction automatically produced in the operation of the machines makes the process rapid and effective.

Having thus described my invention, what I claim as new and desire to protect by Letters Patent is:

1. The process of treating impure petroleum to relieve it of its impurities comprising spraying and atomizing the impure oil

against a rotatable member, spraying hot water into contact with said atomized oil, 20 agitating said mixture and passing the same through a series of vertically arranged chambers where the oil and water may separate by gravity and drawing off the oil.

2. In the treatment of impure petroleum, 25 the improvement comprising spraying said oil, together with a jet of hot water upon a moving baffle, whereby the oil and water are atomized and mixed, agitating the mixture under centrifugal force, and then settling out the impurities by gravity and drawing off the oil.

In testimony whereof I hereunto affix my signature this 21 day of January A. D. 1924.

JOHN F. WRIGHT.
